MECHANICAL PENCIL

Ray Brosseau, Kew Gardens, N. Y.

Application August 16, 1946, Serial No. 690,952

2 Claims. (Cl. 120—17)

1

This invention relates to mechanical pencils and more particularly to pencils in which the writing element is mechanically advanced to writing position.

The principal object of this invention is the provision of a mechanical pencil in which a precision type of positive acting mechanism is employed to advance the writing element to writing position as well as to supply successive writing elements and to bring them into writing position.

Another object of this invention is the provision of a mechanical pencil in which the mechanism for advancing the writing element performs a second function which is that of gripping and holding the writing element in writing position and preventing said writing element from wobbling or becoming displaced.

A further object of this invention is the provision of a mechanical pencil in which the mechanism for advancing the writing element is adapted automatically to advance said writing element a predetermined distance. This and other objects are attained by the mechanism illustrated in the accompanying drawing in which—

Fig. 1 is a side elevational view of a mechanical pencil embodying the feed and holding mechanism herein claimed, the casing of said pencil being partly broken away to expose said mechanism;

Fig. 2 is a fragmentary vertical section through said pencil and through the feed and holding mechanism thereof, said mechanism being shown holding the writing element in writing position;

Fig. 3 is a view similar to that of Fig. 2 showing the first stage in the feeding operation, this stage being solely that of holding the writing element to prevent its longitudinal movement and bring the feeding element into operative position;

Fig. 4 is a view similar to that of Fig. 3 showing a more advanced stage in the operation, this view showing the feeding mechanism about to be placed into operative position; and

Fig. 5 is a view similar to that of Fig. 4 showing the feeding mechanism in operative position and advancing or feeding the writing element.

Referring to Fig. 1 it will be seen that the mechanical pencil 10 herein claimed is provided with a casing or barrel 11, a pocket clip 12, an eraser 13 at the upper end of the casing and a writing element or "lead" 14 extending through a hole in the lower end of the casing. The barrel 11 may be made in two sections as shown in Fig. 1, to wit, the upper section and a lower sec-

2

tion affixed together in any conventional manner. This type of construction will facilitate introduction of the feeding and holding mechanism hereinafter described into the barrel. It will also be noted that an opening or slot 15 is provided in the side of the barrel. The reason for incorporating a slot into the barrel will shortly become apparent.

Referring now to Figs. 2 to 5 inclusive, it will be seen that the lower portion 11a of the barrel is a relatively solid mass having a tubular opening extending longitudinally therethrough to accommodate the writing element 14. Above portion 11a is a hollow chamber 20 and above said hollow chamber is the upper portion 11b of the casing 11, this upper portion comprising also a relatively solid construction. Extending longitudinally through the center of upper portion 11b is a tube 21, said tube extending downwardly in part into the cavity or chamber 20. This tube is a magazine for the writing element 14 and more particularly for a plurality of said elements arranged in line one following the other as shown in said Figs. 2 to 5 inclusive. The writing elements feed through the magazine 21 and as one of said elements is consumed it is followed by another element which takes its place. The dimensions of the magazine 21 are such that the writing elements 14 are slidably mounted therein so that when the pencil is held vertically there is a tendency for these writing elements to move downwardly through and out of said magazine. This may be designated as a gravity feed.

Slidably mounted on the downwardly extending end of magazine 21 is a chuck 25. It will be noted that this chuck is provided with a rather large head 26 and a bifurcated shank 27 which is smaller at the top and larger at the bottom. The lower ends of the bifurcated shank 27 carry 40 the gripping portions or shoes 28. Normally the lower ends of said bifurcated shanks are sprung outwardly as shown in Fig. 4 so that the gripping portions 28 are normally out of contact with the writing element 14.

At the lower end of the chamber 20 is a second chuck 30. Unlike the first chuck 25 which is longitudinally movable on the magazine tube 21, this second chuck 30 is fixed at 31 in a recess formed in the lower solid portion 11a of the barrel 11. This chuck 30 is also provided with a bifurcated shank 32 and gripping portions or shoes 33 are formed on the upper ends of said bifurcated shank. Unlike the shank of chuck 25, the lower end of the shank of chuck 30 is smaller than its upper end. The normal condition of chuck 30 is

its open position shown in Fig. 2, its bifurcated shank being normally sprung outwardly. In such position its gripping portions are out of contact with the writing member 14.

Mounted on the shank of chuck 25 is a collar 40 and mounted on the shank of chuck 30 is a second collar 41, these two collars being joined by means of a yoke 42 with which they are integral. It will be noted that a portion 43 of said yoke extends through the opening 15 in the side wall of the barrel 11. It will also be noted that a plate 44 on the outside of said barrel is affixed to upwardly extending portion 43.

Plate 44 is a finger member by which the collars 40 and 41 may simultaneously be moved in a longitudinal direction, either upwardly or downwardly as the case may be. The normal position of the finger member 44 is shown in Fig. 2. This is its lowermost position. When the finger member 44 is in this position, the yoke 42 and the collars 40 and 41 are also at their lowermost positions. The collar 41 is at the smaller end of the chuck 30 and it is therefore out of engagement with said chuck in the sense that it does not squeeze the two gripping ends of the chuck together. The collar 40 on the other hand is somewhere below the small end of the bifurcated shank 27 of the chuck 25. It is in engagement with said chuck therefore in the sense that it squeezes the two gripping ends of the chuck together so that they in turn are in tight engagement with the writing element 14. This is shown in Fig. 2.

When the writing element 14 is worn down and it is desired to advance it, the finger member 44 is pushed upwardly through the position shown in Fig. 3, to the position shown in Fig. 4. As it is thus moved upwardly the collar 41 is brought into engagement with the thicker end of the chuck 30 and it thereby closes said chuck upon writing element 14. This is shown in Figs. 3 and 4. At the same time collar 40 moves upwardly and it disengages the thicker end of the chuck 25 thereby opening said chuck, it also engages the head 26 of said chuck and pushes the chuck up through the position shown in Fig. 3 to the position shown in Fig. 4. It will be seen that this operation causes chuck 25 to release the writing element 14 but no longitudinal movement of said writing element is thereby permitted for the reason that simultaneously therewith the gripping operation of chuck 30 takes place.

The finger member 44 is now pushed downwardly as shown in Fig. 5. There is no immediate contact made between the collar 40 and the larger lower end of chuck 25. Instead said chuck moves downwardly with the collar 40 simply by virtue of the attraction of gravity upon it. But this free downward movement of chuck 25 is negligible and such movement is arrested by the stop portion 50 which extends inwardly into the chamber 20 from the inner wall of the barrel 11. The lower end of the chuck 25 being sprung outwardly engages said stop portion 50 and further free downward movement of said chuck is prevented. The collar 40 however continues to move downwardly with the finger member 44. As it does so it engages the larger lower end of the chuck 25 and squeezes said end together. This has the effect of causing said chuck to grip writing element 14 and at the same time it frees said chuck from the holding action of the stop portion

50. The chuck 25 now moves downwardly with the finger member 44. At the same time a corresponding downward movement of the collar 40 is caused. This results in opening the lower chuck 30 and thereby causing said chuck to release the writing element 14. Since the upper chuck 25 now engages the writing element, further movement downwardly of said upper chuck 25 will cause a corresponding movement of the writing element 14. When the finger member 44 reaches its lowermost position as shown in Fig. 2, the writing element has been advanced as desired.

15 It will be understood from the foregoing that only a preferred embodiment of the invention has been shown and described. Modifications may be incorporated therein without departure from the spirit of the invention.

20 What has above been described is a positive-action mechanism for mechanical pencils. There are no springs to become loose or to get out of order in the many ways that are common to conventional mechanical pencils. The gripping action on the writing element is sure and the force exerted upon the writing element is equal on all sides thereof. There is, therefore, no unbalanced force which might tend to break the writing element before it leaves the pencil. As a matter of fact, said writing element is protected against breaking even after it leaves the casing of the pencil and when it is in actual writing position. It will be noted in Fig. 1 that the lowermost end of the casing is longer on one side than it is on the other, and that it tapers upwardly from said longer side to the shorter side. The longer end comprises a lip 60 which is adapted to serve as a guard or backrest for the writing element to prevent it from breaking during the writing operation. The shorter end provides considerable clearness for writing purposes.

40 I claim:

1. In a mechanical pencil a feeding mechanism for the writing element, said feeding mechanism comprising a fixed chuck and a movable chuck, a collar for each of said chucks adapted to close and open said chucks, a yoke connecting said collars and a finger member connected to said yoke whereby said yoke and the collars connected thereto may be longitudinally moved to cause upward movement of the movable chuck and at the same time causing said movable chuck to open and said fixed chuck to close and then downward movement of the movable chuck and at the same time causing said movable chuck to close and said fixed chuck to open.

2. In a mechanical pencil in accordance with claim 1, a stop member to engage the movable chuck to prevent its downward movement until the collar of said chuck engages and closes said chuck.

60 RAY BROSSEAU.
